BY ATTORNEYS

UNITED STATES PATENT OFFICE.

EMILIE F. SCHIESS, OF NEW YORK, N. Y.

DESIGN FOR A TAPE-MEASURE.

SPECIFICATION forming part of Design No. 25,973, dated August 25, 1896.

Application filed May 24, 1895. Serial No. 550,577. Term of patent 7 years.

To all whom it may concern:

Be it known that I, EMILIE F. SCHIESS, a citizen of the United States, residing in the city, county, and State of New York, have invented 5 a new and useful Design for a Tape-Measure, of which the following is a full, clear, and exact description.

My invention is a new and original design for a tape-measure holder. (Shown in the 10 accompanying drawing in side elevation.)

The design consists of an elongated casing having projections at each end extending substantially at right angles to the longer axis of the casing and with a rib or projection extending along the casing and between the front and rear projections, said rib being 15 exposed to view. This bar or rib, with the

elongated casing having the right-angular projections at each end of the rib, constitutes the main feature of the invention. 20

I claim—

A design for a tape-holder comprising a body of the shape of a standing pig with a projection between its fore and hind legs and a spindle projecting from its rear and coiled 25 to represent a pig's tail, substantially as described.

In witness whereof I have hereunto set my hand in presence of two witnesses.

EMILIE F. SCHIESS.
